COUPLER FOR JOINTED DOLLS

Jacob Stein, Brooklyn, N. Y.

Application October 8, 1932, Serial No. 636,889

2 Claims. (Cl. 46—40)

The present invention is a rubber doll, and relates more particularly to an improved coupler for joining the head, arms and legs to the body.

An object of the invention is the provision of a very simple and improved coupling means by which the arms, heads, and legs of a doll may be joined to the body thereof with ease and celerity.

Another object of the invention is the provision of coupling member for the arms, legs or head of a hollow rubber jointed doll and which is formed and constructed in such a manner as to very simply and economically provide a sound producing device, when adjacent parts of the doll are compressed.

With the above and other objects in view, the invention further resides in the sundry details of construction, combination and arrangement of parts hereinafter more fully described and pointed out in the appended claims.

In the drawing which shows the preferred embodiment of the invention as at present devised;

Figure 1 is a perspective view of a hollow rubber doll simulating an infant, and made in accordance with the present invention;

Figure 2 is a perspective view of the doll similar to Figure 1, but showing the head, legs and arms disconnected from the body so as to illustrate the details of construction and the manner in which the parts may be assembled or disassembled;

Figure 3 is an enlarged fragmentary view of the body portion of the doll body with parts broken away to illustrate the detailed construction of the joint between the leg or arm thereof;

Figure 4 is a longitudinal sectional view taken through one of the coupling members used in joining the head, arms and legs to the body;

Figure 5 is a side elevation of a modified form of coupling member which may be used for joining both of the arms and legs to the body, as illustrated in dotted lines.

Referring in detail to the drawing in which like characters denote corresponding and like parts throughout the several views, 10 is the hollow body of the doll made of compressible and resilient rubber. The arm 11, leg 12 and head 13 of the doll are also preferably formed of hollow rubber, in any approved manner known to the art, and may take any desired shape or position, but in the drawing, are shown those simulating the arms, legs, head and body of an infant.

The rubber wall forming the body 10 is provided at appropriate points thereof with concaved recesses or sockets 14 in which complementary con-

vexed end portions 15 of the legs and arms of the doll extend and fit. The bottoms of said sockets 14 are formed each with an opening 16 communicating the sockets with the interior of the body. The top part of the body 10 is formed with an upstanding neck portion having a frusto-convexed outer surface and provided with a central opening 18 coaxial thereof and communicating with the interior hollow body 10. The head 13 of the doll is formed at its neck portion with a socket 14a complementary to the neck of the body and in which the latter extends. The bottom of the socket 14a is formed with opening 16a similar to openings 16.

The convexed end portion 15 of the arms and legs are also formed with openings 19 extending coaxially therewith.

The head 13 and the arms 11 and the legs 12 are joined to the body by either of the improved coupling means, shown in Figs. 4, or 5. This coupling means may be of any suitable material, but preferably consists of a block of rubber 20 cylindrical in cross-section and having one end provided with an enlarged head h shaped after the manner of a button and of larger diameter or width 25 than that of the openings 16 and 16a.

The shank portion of a coupling 20 is inserted in an opening 19 of an arm or leg or in the opening of the neck portion and is secured therein by adhesive, such as a rubber cement, or may be 30 vulcanized therein, with the button end h spaced from the extremity of the arms, legs and neck portion sufficiently, at least, to equal the thickness of the rubber stock at the openings 16 in the body and 16a in the head. This button portion h 35 may be inserted in the opening 16 of the body and the opening 16a of the head, because of the stretchable or yielding character of the material forming the coupling member 20 and surrounding the openings 16 to 16a coupling member.

When 40 the parts have been properly assembled they will take the position shown in Figure 3, that is, with the convexed end 15 of the arms and legs and the neck portion 17 fitted in the sockets 14 and the button portion h of the coupling member lying 45 adjacent the inner face of the body or head portions of the doll, with the shanks s of the coupling 20 extending through the openings 16 and 16a. This construction permits the arms and legs and head to move or swivel about the axis of their 50 coupling members 16.

The coupling members 20 are further provided with a passage or bore 21 extending, preferably, longitudinal therethrough. One end of the bore is reduced or obstructed by a very thin film or 55

layer of rubber 22 or other suitable material, which is preferably perforated as at 23, or which is so positioned with respect to the bore as to form a reed. Thus, when the head portion, or body portion or the arm and leg portions of the doll are squeezed or compressed the air in the said compressed portion will be moved through the passage or passages 21 of a coupling member and cause the reed 22 to vibrate, thus producing a 10 whistling or crying sound.

The coupling members as above stated are preferably formed of molded rubber, and, in the molding operation, usually a very thin film is left at the end of the core forming the bore or passage 15 21, thus covering the end of the passage, and by merely perforating or slitting this film, the reed or sounding producing element 22 is provided. However, if such film is not so produced, the reed 22 may be provided by placing across the passage 20 21 a thin layer of rubber or other thin tissue material or any other desired material in any approved or desired manner.

In Fig. 5, is shown a modified form of the coupling member 24 and differs from the coupling member 20 only in that it is made of greater length so that a single coupling member 24 may be used for joining both legs or arms of the doll to the body, as shown in dotted lines. In this form of the invention, the button head *h* thereof extends into and engages the interior walls of the 30 hollow leg or arm portions.

In this specification and the annexed drawing, the invention is disclosed in the form in which it is considered to be the best, but the invention 35 is not limited to such form because it is capable of being embodied in other forms; and it is to be

understood that in and by the claims following the description herein it is intended to cover the invention in whatever form it may embody within the scope thereof.

Having thus described the invention, what is 5 claimed is:

1. In a joint connection for jointed hollow rubber dolls, the combination with the body and limbs of the doll, said body having concaved sockets therein and the limbs having complementary projecting end portions to fit in said sockets, said sockets each having an opening in the bottom and extending through the wall thereof and said end portions of the limbs having coaxial openings therein, of a coupling member joining said limbs 15 and body together and comprising a shank of rubber having one end fixedly secured in an opening of one of said limbs and extending through the openings in opposite sockets and the opening in the end portion of an opposite limb, said 20 shank being rotatable in said last mentioned opening, and an enlarged rubber head on the other end of said shank larger than said last opening, whereby the elements of the doll are movably jointed together. 25

2. In a joint connection for jointed rubber dolls, a rubber coupling member for jointedly connecting together hollow compressible body parts of a doll and being formed with a passage therethrough and a thin film of rubber across said passage, said film of rubber being ruptured to permit passage of air therethrough, whereby said film may vibrate to produce sound when said rubber body parts are compressed. 30
